UNITED STATES PATENT OFFICE

WILLY FROMM, OF FRANKFORT-ON-THE-MAIN, GERMANY, ASSIGNOR TO UNITED SHOE MACHINERY CORPORATION, OF PATERSON, NEW JERSEY, A CORPORATION OF NEW JERSEY

FASTENING DISTRIBUTOR

Application filed May 23, 1928, Serial No. 280,107, and in Germany October 18, 1927.

My invention relates to apparatus by which such fastenings as nails and tacks are supplied to machines by which they are inserted. An example of a machine of this 5 character is furnished by one of those employed to attach heels to shoes.

In a much used type of distributor, the 10 nails are delivered from their source to slotted raceways, down which they descend supported by their heads. If the nails thus fed are to be employed in a machine in which heel-attaching nails are to be driven from the inside of a jack, or otherwise inserted with their points upmost, it becomes 15 necessary to reverse them. A convenient device for this purpose involves fixed abutments, against which strike the shanks of the nails suspended upon the raceways, the points being thus retarded, while the heads pass on over the ends of the raceways and fall first into the jack. In an organization 20 of this character, some poorly formed nails, as those having irregular fins or projections beneath the heads, or on which the under sides of the heads are conical, impose particularly trying conditions. The resistance produced by their contact with the raceways, added to the resistance of the reversing 25 abutments, may stop them before they overbalance, so that they rest, forwardly inclined, with their heads upon the raceways and their shanks upon the abutments. This 30 clogs the raceways against the advance of succeeding nails. An object of this invention is to insure the regular advance of nails or other fastenings through the raceways, regardless of the frictional resistance they offer, and especially to obtain this positive 35 movement at the points of maximum resistance, as when they engage the reversing device. For this purpose, I associate with each raceway a clearing member, acting upon fastenings in the raceway while said fastenings are under the influence of a reversing device. 40 Since the raceway is inclined in the direction of delivery, the clearing member most advantageously acts in the same direction, not only freeing the clogged fastenings, but also urging them forward. Whatever may be the 45 location of the clearing member, I prefer to

move it about two axes, there being means for preventing this movement about each axis during movement about the associated axis. One axis is shown as possessing a movement of translation, and such movement is governed by a difference in the resistance to 55 turning about the axes. By such an arrangement, there may be imparted to a member its clearing movement in a direction substantially parallel to the raceway in engagement with a fastening, and then a return travel elevated above the raceway, entirely clear 60 of the fastenings, and thus free from interference with their delivery. Lack of exact 65 parallelism to the raceway in the clearing movement and irregularities in the engagement with the fastenings may be compensated for by a yield of the member. Since 70 ordinarily a plurality of raceways are to be maintained against clogging, a corresponding 75 number of clearing members are employed. These are herein illustrated as mounted together upon a spindle fast in spaced arms secured to a shaft which rotates in carrier-arms fixed to a primary shaft. These shafts determine the axes previously mentioned. The governing resistance to movement is preferably in the form of a friction device or brake acting upon the primary shaft. The driving connection for 80 the mechanism may be applied to one of the spindle-carrying arms.

In the accompanying drawings,

Fig. 1 is an end elevation of a nail-distributor, with which is associated a particular embodiment of this invention, my improved clearing mechanism being shown in full lines, and the previously used elements of the distributor being in dotted lines;

Fig. 2 is a broken perspective view of the 90 clearing mechanism;

Fig. 3, a view showing the distributor partly in vertical section and partly in side elevation; while

Figs. 4 to 7, inclusive, are details illustrating successive positions of the clearing mechanism.

I have chosen to disclose my invention as combined with a distributor in which nails are fed from a mass in a rotatable drum 10 100

to a series of downwardly inclined raceways, each furnished by a pair of parallel bars 12, 12. Down these raceways the nails travel under the influence of gravity, supported by their heads resting on the tops of the bars and with their shanks hanging vertically, and are picked off one by one in each raceway, in sets, by oscillatory delivery-disks 14 mounted near the lower extremities of the raceways. Rake-wheels 16, supported upon a constantly driven shaft 18 journaled transversely of the forward end of the casing of the drum 10, co-operate with the raceways to free these of crossed nails. Assuming that the nails are to be driven points up, they are reversed before leaving the raceways by contact of their shanks with abutments 20 mounted between the bars 12. These abutments, restraining the lower portions of the 20 nails in their advance, cause the heads to assume a leading position, so that on delivery at the ends of the raceways these heads are down. As so far outlined, the distributor-elements are well known. As the abutments hold back nails, there is added to the friction of the heads upon the raceways a resistance to delivering movement which produces a tendency for the nails to clog at the reversing points and stop the feed. Keeping the raceways clear involves a waste of time on the part of the operator, and if the clogging escapes attention, heels may be attached without the full number of nails.

Journalized across the raceways, above the abutments 20, in brackets 22, 22 fixed to the distributor-frame, is a primary shaft 24 of my clearing mechanism. Secured to the shaft outside the brackets are carrier-arms 26, 26 downwardly and forwardly inclined, and rotatable in the outer extremities of these arms is a secondary shaft 28. To the shaft 28, just within the arms 26, 26, are fixed two arms 30 and 32, and in the rear extremities of these is fastened a spindle 34. Mounted upon the spindle over each raceway is a holder 36, in the rear face of which are ways to receive a clearing member 38 arranged to yield vertically against gravity. A projection 40 from the upper end of each clearing member, by its contact with the top of the holder, limits the downward movement of the member. The lower extremity of the clearing member is beveled at the rear, producing a surface 42, which, in the clearing movement, approaches parallelism with the nail-supporting surfaces of the raceways. This surface forms with the upper side of the member a point which is effective for engagement with the heads of the nails. Oscillation of the arms 30 and 32 about the axes of both the shafts 24 and 28, and a consequent movement of the clearing members, is effected by driving connections to the arm 32. This arm has from its outer side a projection 44, to which is articulated an

eccentric-rod 46, the strap 48 of which surrounds an eccentric 50 secured to the shaft 18. The extent to which the arm 32 may move about the axis of the shaft 28 is limited by contact-portions upon the arm, these contact-portions being shown as provided by opposite screws 51, 51 threaded through the arm at the ends of a transverse slot therein. These screws, upon movement of the arm, contact with the shaft 24, and by their adjustment may be caused to vary the extent of oscillation in either direction. To cause successive rotation of the shafts 24 and 28, and thus the movement of the clearing members in predetermined paths, the rotation of the shaft 24 is retarded by a friction-brake, shown as consisting of collars 52 and 54, respectively fast and loose upon the shaft, the collar 54 being pressed against its companion by a spring 56 encircling the shaft and bearing against the collar 54 and the adjacent bracket 22.

Considering one of the raceways and its clearing instrumentality, as illustrated in Figs. 4 to 7, inclusive, a nail N appears in Figs. 4 and 5 caught upon its raceway and co-operating abutment. In Fig. 4, the clearing member 38 of this raceway is at its highest and most rearward position. This relation obtains when the eccentric 50 thrusts the arm 32 forward to the maximum extent. With the continued rotation of the eccentric in the direction of the arrow in Fig. 3, the arm 32 is drawn from the position shown in Fig. 4, in which the right-hand screw 51 is against the shaft 24, to that of Fig. 5, in which the left-hand screw contacts with the shaft. This movement, with the companion arm 30, occurs about the axis of the shaft 28, the brake device 52, 54 at this time holding the shaft 24 against turning. Each holder 36, carried upon the spindle 34, is thereby lowered from the point *a* to the point *b*, the path being indicated by dashes. The point of the clearing member 38 is brought into contact with the tops of the bars 12 forming a raceway, said member yielding in its ways to compensate for excess of downward movement of the holder. The arm 32 being checked in its movement by the contact of the left-hand screw 51 with the shaft 24, continued rotation of the cam, exerting a driving force upon the arm 32 in the same direction as just described, causes this and the arm 30 to swing about the axis of the shaft 24, the axis of the shaft 28 having a movement of translation. Each holder 36 is thereby caused to follow a path approaching parallelism with the surface of the raceway, this being from *b* to *c*. The point of the clearing member 38 slides along the upper edges of the raceway-bars. During this portion of its movement, the clearing member engages the head of the retained nail N and sweeps this forward over the raceway, positively urging

it down for delivery. At the completion of this clearing action, the elements are related as appears in Fig. 6. Now the eccentric has passed the center and begins to move the arm 32 in the opposite direction. The left-hand screw of the arm 32 leaves the shaft 24, which is again temporarily held against rotation by the friction device 52, 54, and the arm 32 turns about the axis of the shaft 28 until the right-hand screw reaches the shaft 24. This quickly raises the holder from *c*, at which it finished its clearing stroke, to *d*, where the point of the member 38 is elevated above the upper edges of the raceway-bars similarly to its initial position, so it cannot interfere with the feed of the nails. This relation is as illustrated in Fig. 7. While the eccentric is completing its 360 degrees of rotation, the stopping of the oscillation of the arm 32 about the axis of the shaft 28 by contact with the right-hand screw 51, and its movement about the axis of the shaft 24, restores the holder and clearing member to the initial position. During this return-travel, the point 25 of the member is at all times free from contact with the heads of the nails in the raceway, so there is no tendency to move them oppositely to the direction of delivery. The extent of movement of the clearing members toward and from the raceways may be varied by adjustment of the screws 51, 51.

Having described my invention, what I claim as new and desire to secure by Letters Patent of the United States is:

1. In a fastening-distributor, a raceway for fastenings, a fastening-reversing device co-operating therewith, and a clearing member acting upon the fastenings while they are under the influence of the reversing device.

2. In a fastening-distributor, an inclined raceway, a fastening-reversing device co-operating therewith, and a clearing member acting upon the fastenings in the direction of downward inclination of the raceway and while they are under the influence of the reversing device.

3. In a nail-distributor, a raceway constructed and arranged to convey nails supported by their heads, a reversing abutment located for contact with the shanks of the thus-supported nails, and an oscillatory member mounted above the abutment and movable into contact with the heads of the nails upon the raceway.

4. In a nail-distributor, a raceway, a clearing member co-operating therewith and alternately movable about two axes, one of said axes having a movement of translation, and means arranged to variably limit the travel of the member.

5. In a nail-distributor, a raceway, a clearing member co-operating therewith and alternately movable about two axes, and means arranged to produce a difference in the resistance to movement about the two axes.

6. In a nail-distributor, a raceway, a clearing member co-operating therewith and alternately movable about two axes, one of said axes having a movement of translation and the other being fixed, and means arranged to increase the resistance to rotation about the fixed axis. 70

7. In a nail-distributor, a raceway, a shaft, a carrier fixed to the shaft, an arm rotatable upon the carrier and limited in its movement by the shaft, and a clearing member mounted upon the arm for co-operation with the raceway. 75

8. In a nail-distributor, a raceway, a shaft journaled in proximity to the raceway, a carrier fixed to the shaft, an arm rotatable upon the carrier, actuating connections to the arm, and a clearing member mounted upon the arm for co-operation with the raceway. 80

9. In a nail-distributor, a raceway, a shaft journaled in proximity to the raceway, a carrier fixed to the shaft, an arm rotatable upon the carrier, and a clearing member movable upon the arm for contact with the raceway. 85

10. In a nail-distributor, a raceway, a shaft, a carrier fixed to the shaft, an arm rotatable upon the carrier, said arm being limited in its movement by contact with the shaft, and a clearing member movable upon the arm for contact with the raceway. 90

11. In a nail-distributor, a raceway, a shaft journaled in proximity to the raceway, a carrier fixed to the shaft, an arm rotatable upon the carrier, a member adjustable upon the arm and contacting with the shaft, and a clearing member mounted upon the arm for co-operation with the raceway. 100

12. In a nail-distributor, a raceway, a rotatable shaft, a carrier fixed to the shaft, a friction device arranged to resist the rotation of the shaft, an arm rotatable upon the carrier, and a clearing member mounted upon the arm for co-operation with the raceway. 105

13. In a nail-distributor, a plurality of raceways, a primary shaft journaled above the raceways, carriers spaced from each other upon the primary shaft, a secondary shaft journaled in the carriers, arms spaced from each other upon the secondary shaft, a spindle fast in the arms, and clearing members mounted upon the spindle and co-operating with the raceways. 110

14. In a nail-distributor, a plurality of raceways, a primary shaft journaled above the raceways, carriers spaced from each other upon the primary shaft, a secondary shaft journaled in the carriers, arms spaced from each other upon the secondary shaft, a driving connection arranged to oscillate one of the arms, a spindle fast in the arms, and clearing members mounted upon the spindle and co-operating with the raceways. 115

15. In a nail-distributor, a plurality of raceways, a primary shaft journaled above the raceways, carriers spaced from each other 120

upon the primary shaft, a secondary shaft journaled in the carriers, arms spaced from each other upon the secondary shaft, oppositely extending screws carried by the arms and arranged for contact with the primary shaft, a spindle fast in the arms, and clearing members mounted upon the spindle and co-operating with the raceways.

16. In a nail-distributor, a plurality of raceways, a primary shaft journaled above the raceways, a brake acting upon the shaft, carriers spaced from each other upon the primary shaft, a secondary shaft journaled in the carriers, arms spaced from each other upon the secondary shaft, a spindle fast in the arms, and clearing members mounted upon the spindle and co-operating with the raceways.

17. In a nail-distributor, a raceway, and a clearing member co-operating therewith and alternately movable about two axes, there being means for preventing movement of the member about each axis during its movement about the associated axis.

18. In a nail-distributor, a raceway, a yieldable clearing member contacting therewith, and a support for the member alternately movable about two axes, there being means for preventing movement of the member about each axis during its movement about the associated axis.

19. In a nail-distributor, a raceway, and a clearing member co-operating therewith and alternately movable about two axes, one of said axes having a movement of translation and there being means for preventing movement of the member about each axis during its movement about the associated axis.

In testimony whereof I have signed my name to this specification.

WILLY FROMM.
